CLAIM

The ornamental design for an armrest mouse pad, as shown and described.

DESCRIPTION

FIG. 1 is a top isometric view of an armrest mouse pad. FIG. 2 is a bottom isometric view of the armrest mouse pad of FIG. 1.

FIG. 3 is a top view of the armrest mouse pad of FIG. 1. FIG. 4 is a bottom view of the armrest mouse pad of FIG. 1.

FIG. 5 is a right side view of the armrest mouse pad of FIG. 1.

FIG. 6 is a left side view of the armrest mouse pad of FIG. 1.

FIG. 7 is a front view of the armrest mouse pad of FIG. 1; and,

FIG. 8 is a rear view of the armrest mouse pad of FIG. 1. All broken lines seen in the drawings depict portions of the armrest mouse pad that form no part of the claimed design.

1 Claim, 6 Drawing Sheets
